ANDREAS VALDEMAR CHRISTENSEN, OF ODENSE, DENMARK.

WATER-CLOSET FIXTURE.

1,174,123.

Specification of Letters Patent. Patented Mar. 7, 1916.

Application filed April 29, 1913. Serial No. 764,348.

To all whom it may concern:

Be it known that I, ANDREAS VALDEMAR CHRISTENSEN, plumber, subject of the Kingdom of Denmark, residing at Odense, Denmark, have invented certain new and useful Improvements in Water-Closet Fixtures, of which the following is a specification.

The invention relates to improvements in water closet fixtures.

10 The object of the present invention is to improve the construction of water closet fixtures and to provide a simple, efficient, and comparatively inexpensive water closet fixture equipped with a container located below the frost line and into which the water from the pipe connections of the flush tank is completely drained after the said tank has been flushed, whereby the exposed parts 15 of the fixture above the frost line will be free from frost and ice, and effectually prevented from becoming inoperative through freezing.

A further object of the invention is to provide a water closet fixture of this character, equipped with means for creating a 25 partial vacuum within the container, and for drawing off a portion of the water contained within the same while the flush tank is being filled, whereby the excess of water 30 will be rapidly drained into the container after the tank has been flushed.

The details of the invention, and especially the way in which the water-pipe is filled and emptied, will appear from the following specification and are furthermore 35 illustrated by the accompanying drawings, which show one form of construction and in which:

Figure 1 is a side elevation partly in section of a water closet fixture constructed in accordance with this invention; Fig. 2 is an enlarged sectional view of the drain tank or container; Fig. 3 is a detail sectional view showing the construction of the automatic ball valves.

For the sake of simplicity, the water-pipe is shown only connected with a single flushing-tank.

In the accompanying drawing 1 is the 50 flushing-tank, 2 is the outer part of the siphon, 3 is a float disposed on and secured to the latter or the said float 3 may be connected therewith by any suitable means, 4 is the handle, 5 is the lever, and 6 is the water-pipe. Inside the water-pipe and throughout its entire length there is disposed a rod

7, which, for each floor or each water-closet (flushing tank), is provided with a suitable engaging-member, for instance, the U-shaped member 8 shown in the drawing. 60 On the pipe 6 there are disposed, at corresponding points, a casing 9 which is provided with tight bearings for the axle 10 of the lever 5, which axle actuates the member 8, for instance by means of a cam or 65 crank-arm 11 disposed between its branches. Down below (at a frost-free depth) the pipe 6 ends in a socket 12 on the cover of a tank 13. The rod 7 is, at its lower end, connected with a pipe 14, whose upper end is 70 inserted in the socket 12, and which is passed through a packing-box 15 in the cover of the tank. The pipe 14 is, at its lower end, connected with an injector cone 16, whose nozzle 17 has an elongation 18, which at its 75 lower end is provided with the aforesaid main-valve 19. The valve-casing 20 of this valve, which is provided with guides for the members 17 and 18, is secured to the bottom 80 of the tank, or chamber, 13, and at its lower end it is connected with the main water-pipe 21.

When the valve 19 is open, as shown in the drawing, the water from the pipe 21 will run through holes 22 into the injector 18, 17, 85 and through the injector-cone 16 up into the pipe 14, at the top of which it runs out through holes 23 and then rises up in the water-pipe 6. As a result of the effect of the injector, a part of the water remaining 90 in the closed tank 13 will be sucked up through the pipes 14 and 6, and the air above the water in the tank 13 will be rarefied. The significance of this will appear 95 from the following: The aforesaid opening of the valve 19 and the rising of the water in the pipe 6 is due to the fact that, by pulling the handle 4, the lever 5 is turned into the position shown in the drawing, thereby causing the cam 11 on the lever's axle 10 100 to actuate the lower branch of the member 8, thus forcing the rod 7, together with the parts 14, 16, 17, 18 and 19 connected therewith, downward a suitable distance. At the same time a valve 26, in a connection between the water-pipe 6 and the tank 1, is 105 opened by means of rods 24 and 25, so that the water can run into the tank 1. When the water has risen to a certain height in the tank 1, the float 3 is lifted, and thereby 110 also the siphon-member 2, and when the siphon acts, the tank is emptied.

The siphon-member 2 or the float 3, carries a rod 27, which is passed through the cover of the tank and at its top end has a suitable head 28. The said latch 29, which 5 catches onto a projection 30 on the lever 5, also has a jointed projection, or pawl, 31, which can be passed by the head 28 on its upward stroke but is pulled down by the head on its downward stroke. This latter 10 movement is made as soon as the siphon has acted, the members 2, 3, 27 and 28 then falling again. The latch 29 which, together with the projection or pawl 31 has the form of an angle-lever, will then be turned and 15 released from the projection 30 on the lever 5, so that the latter is liberated and returns to its normal position, for instance under the influence of a spring 32. Thereby the valve 20 26 is closed, and the cam 11 is brought into the position 11^a shown by the dotted lines. It is obvious that this normal position does not prevent the levers 5 and thereby the rod 25 7, 8, together with their appertaining members, in the water-closets on the floors above and below the water-closet here in question from functioning in the aforesaid manner. In other words, this invention can be made use of in an optional number of water-closets situated immediately above one another which can all be flushed in the usual 30 manner independently of one another. When the cam 11 is turned back into the position 11^a, a spring 33, or the like, which may be disposed at the top end of the rod 7, 35 will with the assistance of the water pressure from the supply close the valve 19, and the water in the pipe 6 will run back into the tank 13, where, as before mentioned, there is a low pressure. Besides the afore- 40 said holes 23, the pipe 14 may also have other, somewhat lower situated holes 34 which, when the valve 19 is closed, are lifted up to a level with the lower edge of the socket 12; so that even the socket 12 is 45 emptied of water.

In order that the tank 1 may be completely emptied, there may be disposed between its bottom and the water-pipe 6 a connecting pipe 35 with an automatic valve, for 50 instance a ball-valve, 36 which closes the connection when there is an excess of pressure in the pipe 6 and opens it when the pressure falls. Fig. 3 of the drawings shows the operation of the valve, representing the same in its upper position when it is open. In its lower position the ball rests on the ribs 36^b. The spring 33 may be disposed in a special prolongation 37 of the top end of the pipe 6, and from there a pipe 55 38 may lead to the upper flushing-tank or its flushing-pipe, so that the pipe 6 is above in open connection with the atmosphere. The prolongation 27 of the pipe 6 is provided at its upper end with an automatic valve similar 60 to the valve 36, for closing the passage

through the prolongation to prevent the water from flowing through the pipe 33 when the valve 19 is open. The construction of this valve is shown in Fig. 3, it being identical with the valve 36.

70

Instead of closing the tank 13 tightly and producing a sub-pressure in it by means of the injector 16, 17, the tank 13 may also be furnished with a regulated air-connection (cock, valve, or the like), which is closed 75 when the main valve 19 (and the valve or one of the valves 26) is opened, and is kept closed as long as the flushing lasts, but is opened as soon as the flushing is finished. Then the water in the pipe 6 will also be 80 able freely to run down into the tank 13. The regulating of this air-connection may be accomplished in a suitable manner from the rod 7, the lever 5, or the like. The rod 7, 8, or a similar, maneuvering member, does 85 not need to be disposed inside the pipe 6, but may be disposed along the side of it or entirely independent of it.

I claim:

1. A water closet fixture including a flush 90 tank, a closed container located below the frost line, pipe connections between the container and the flush tank through which water passes to supply the flush tank, and mechanism for controlling the flow of water 95 to the flush tank, means for establishing a communication between the pipe connections and the container after the tank has been flushed, whereby the excess of water is drained off and collected, and means for re- 100 turning water from the container to the flush tank when the water is turned on.

2. A water closet fixture including a flush tank, a container located below the frost line, pipe connections between the container 105 and the flush tank through which the water passes to supply the flush tank, mechanism for controlling the flow of water to the flush tank, said mechanism having means for establishing a communication between the 110 pipe connections and the container after the tank has been flushed, and a drain pipe connected with the bottom of the flush tank and with the said pipe connections and provided with a normally open valve arranged 115 to be automatically closed by pressure within the said pipe connections.

3. A water closet fixture including a flush tank, a container located below the frost line, pipe connections between the container 120 and the flush tank through which water passes to supply the flush tank, and mechanism for controlling the flow of water to the flush tank, said mechanism having means for creating a partial vacuum within the container and for establishing a communication between the same and the pipe connections, whereby the excess of water is drained off 125 after the tank has been flushed.

4. A water closet fixture including a flush 130

5 tank, a container located below the frost line, pipe connections between the container and the flush tank through which water passes to supply the flush tank, and mechanism for controlling the flow of water to the flush tank, said mechanism having means for establishing a communication between the container and the pipe connections after the tank has been flushed, and provided also
10 10 with an injector arranged to remove a portion of the water from the container and to produce a partial vacuum therein.

15 5. A water closet fixture including a flush tank, a container designed to be located below the frost line, pipe connections between the container and the flush tank, a supply pipe, a tubular member having a valve for controlling the flow of water from the supply pipe and forming a passage between the latter and the said pipe connections, said tubular member being also provided with means for establishing a communication between the pipe connections and the container after the tank has been flushed.

20 25 6. A water closet fixture including a flush tank, a container designed to be located below the frost line, pipe connections between the container and the flush tank, a supply pipe, a tubular member extending through the container and connected at one end with the said pipe connections and at the other end with the supply pipe, said tubular member being provided at the latter end with a valve for controlling the flow of water to the flush tank and forming a communication between the pipe connection and the container when the valve is closed.

30 35 7. A water closet fixture including a flush tank, a container designed to be located below the frost line, pipe connections between the tank and the container, a supply pipe, a valve for controlling the flow of water from the supply pipe and the said pipe connections and having means for establishing a communication between the pipe connections and the container when the said valve is closed, an operating lever, a rod connected with the valve, and a crank element carried by the lever in the oscillatory movement 40 45 thereof and arranged to actuate the rod to open and close the valve.

50 8. A water closet fixture including a flush tank, a container designed to be located below the frost line, pipe connections between

the tank and the container, a supply pipe, 55 a valve for controlling the flow of water from the supply pipe and the said pipe connections and having means for establishing a communication between the pipe connections and the container when the said valve is closed, an operating lever connected with the said valve, a catch for holding the operating lever to maintain the valve in its open position, and float actuated means for controlling the discharge of water from the flush tank and for releasing the operating lever.

9. A water closet fixture including a flush tank, a container designed to be located below the frost line, pipe connections between the tank and the container, a supply pipe, a valve for controlling the flow of water from the supply pipe and the said pipe connections and having means for establishing a communication between the pipe connections and the container when the said valve is closed, an operating lever connected with the said valve, a catch for holding the operating lever to maintain the valve in its open position, and a float actuated siphon having means for releasing the operating lever from the catch.

10. A water closet fixture including a flush tank, a container designed to be located below the frost line, pipe connections between the tank and the container, a supply pipe, a valve for controlling the flow of water from the supply pipe and the said pipe connections and having means for establishing a communication between the pipe connections and the container when the said valve is closed, an operating lever connected with the said valve, float actuated means for controlling the discharge of water from the flush tank, a spring controlled lever for locking the operating lever to retain the valve in its open position, and a detent carried by the spring controlled lever and arranged to be engaged by the float actuated means for releasing the operating lever.

In testimony whereof I have affixed my signature in presence of two witnesses.

ANDREAS VALDEMAR CHRISTENSEN.
